UNITED STATES PATENT OFFICE.

VICTOR G. MOSS, OF CLEVELAND, OHIO, ASSIGNOR TO THE CHAMPION REGISTER COMPANY, OF CLEVELAND, OHIO, A CORPORATION OF OHIO.

FIREPROOF ACCOUNTING CABINET.

1,409,756.

Specification of Letters Patent. Patented Mar. 14, 1922.

Application filed January 5, 1920. Serial No. 349,609.

To all whom it may concern:

Be it known that VICTOR G. Moss, citizen of the United States, residing at Cleveland, in the county of Cuyahoga and State of 5 Ohio, has invented certain new and useful Improvements in Fireproof Accounting Cabinets, of which the following is a specification.

This invention relates to what is known 10 as a fireproof accounting cabinet, of a style adapted particularly to be used by grocery and other merchants with whom customers keep open or running accounts of daily or less frequent purchases, and which renders 15 a slip holder of ready reference especially desirable, and the invention is an improvement in or upon the construction of a cabinet and parts therein of the class or kind shown in Letters Patent to Frank G. Marchbach and bearing date of Dec. 10, 1918 and numbered 1,287,381.

In the accompanying drawings, Fig. 1 is a sectional elevation of the cabinet front to rear with the cover and hood beneath in 20 closed position, and Fig. 2 is a cross section on line 2—2, Fig. 1. Fig. 3 is a sectional elevation corresponding to Fig. 1, but showing the cover and hood removed and some of the foldable leaves or pads in raised position. 25 Fig. 4 corresponds in the main to Fig. 3 and shows a group of leaves in partially raised position. Fig. 5 is a fragmentary section of the body of cabinet and the cover and the brace for supporting the cover in raised position, and Fig. 6 likewise is a fragmentary section showing especially the spring-pressed lock to hold the said brace as shown. Fig. 30 7 shows a section of both the cabinet body and the cover with the cover down and the 40 brace lock or bolt depressed into disengaging position, as hereinafter more fully described. Fig. 8 shows a section of one of the pads or leaves and the form of the hinge joints thereon. Fig. 9 shows sections of 45 three of the leaves hinged together and connected by hinges of toggle link pattern as disclosed in Fig. 8.

The body *b* and the foldable cover *c* will be understood as being adapted to be filled 50 with asbestos or other fire-proof material, as shown, for example, in the patent above referred to and as is now a common practice in this style of cabinets, and hence the cabinet as such does not in itself constitute subject matter claimed herein. This is true,

also, of all the other parts shown except those which are specifically described and claimed. This reduces the application to the memorandum leaves, folders or holders *d* of whatever form desired, the hood and the 60 means for locking the cover in raised position. The said leaves or slip holders *d* are now being variously constructed but a favorite way is to provide them with clips or spring-pressed supports behind or under 65 which memorandum or sales slips can be filed in rows or pockets in alphabetical or numerical order. As to said clips or holders, a number of spring clips or holders can be employed on each leaf in rows. The 70 present invention does not involve any particular means and therefore no clips or holders are shown.

In the closed position of the cabinet all the pads or leaves *d* are folded upon each 75 other, as seen in Figs. 1 and 2, and in this position they rest upon the bottom plate 2 in superposed relations and to which plate the lower leaf is hinged so as to be foldable back into an inclined upright position. A 80 T-shaped hinge member 3 is employed, and all the pads have similar hinges, and when said hinges are united as shown they give a toggle hinge or link effect in which the leaves are adapted to be raised one at a time, 85 or several at a time, as suggested in Fig. 4. The said hinge members or hinges 3 are shown herein as riveted to the leaves or plates *d*, but preferably they are electrically welded thereon, and when the cover *c* is 90 raised the leaves are adapted to the folded up and back into open and more or less inclined position before the cover as seen in Fig. 3. But as opening of the leaves proceeds they also drop down in the cabinet the 95 depth of the hinge, and after several of the leaves have been opened, Fig. 3, the opening of the next leaf will not only make a corresponding drop of all the open leaves behind it but it will operate somewhat as a lever to 100 force the other closed leaves with the plate 2 to which the lower leaf is hinged forward equal to the width of the hinge thereon. The said plate 2 constitutes the fixed top of the carrier or movable frame 4 in which the 105 drawer 7 is slidably mounted, and said carrier has casters 5 running on the bottom of the cabinet and is adapted to move outward step by step as the leaves are unfolded after the sixth leaf has been raised, and the car- 110

rier is limited in its forward movement by stop 8 at the front of the cabinet adapted to be engaged by the front caster. When all the leaves have been folded down in the 5 cabinet the carrier is pushed back and the cabinet is ready to be closed.

For this purpose I employ, first, a protecting hood *h* which is adapted to cover over and enclose the pile of leaves *d* and to rest 10 down upon the plate 2 about its edge, and the top or outer cover *c* closes over the said hood. The said cover *c* being a fairly heavy member and occupying an upright position when 15 open it is desirable to have the same fastened in said position against accidental dropping or closing, and preferably with such means as will require thought and purpose to let it down. To these ends I employ a longitudinally slotted brace 10, Fig. 20 5, which is adapted to run on a pin or projection 12 engaged in said slot at all times and a recess or cavity in the outer end of the slot serves as rest for the pin when the cover or lid is raised and through which 25 the bracing effect is obtained. Then in order that the brace may not be inadvertently released I provide a locking bolt to hold the brace in said recess and which is not designed to be released until all the leaves are 30 folded and the hood is placed in position thereover. It will be noticed that the said bolt is differential, having an inner stem 14, a body portion 15 and a relatively reduced outside end 16, and a tubular housing 35 or cap 18 fixed in the wall of the cabinet serves as a support for said bolt. A spring 20 is interposed behind said body 15 about the headed stem 14 in the said cap to press the bolt outward. When the cover *c* is raised 40 and the hood removed the said bolt is pressed outward by said spring and the body 15 is projected over the brace and prevents lifting the brace out of its recess. The hood *h* is provided with a beveled lug 22 adapted to 45 bear against the end of the bolt and press it inward when the hood is placed over the leaves, and which forces the bolt back and

brings the reduced end 16 over the brace with room to release the same from pin 12 and slide the brace along to closing position. 50

The several leaves *d* have borders 25 along their side edges corresponding in depth to the depth of the hinges or links 3, so that in the pile the said plates rest horizontally upon each other and the space on each side 55 of the leaf affords room for the holding means to be placed thereon for the account slips.

It will be noticed that the links 3 are at right angles to the leaves and of uniform 60 depth at the sides of the plate and adapted to fall into straight lines with each other in both folded and open positions, thereby forming a brace against the rear wall of the cabinet when open.

Respecting the hood *h* as an element, it will be noticed first that it effectually closes in the pile of leaves for protection when the cover *c* is raised, and that the cover cannot be closed until the hood has been placed 70 in position because it alone carries the means by which the bolt for locking the brace 10 is released. There is therefore a conjoint use between the hood and the cover.

What I claim is:

1. A cabinet as described, comprising a hinged cover having a longitudinally slotted brace and means to engage at the end of said slot and hold the brace in bracing relations, and a differential bolt slidably mounted in 80 the cabinet and adapted to lock the brace at its larger diameter and to release it at its smaller diameter.

2. A cabinet as described having a slotted brace and means to engage and lock the brace 85 in bracing position, and a hood provided with a projection at its side adapted to disengage said locking means and allow the cover to be closed.

Signed at Cleveland, in the county of 90 Cuyahoga and State of Ohio, this 12th day of August, 1919.

VICTOR G. MOSS.
